EXPLOSIVE AMMUNITION AND A METHOD OF MANUFACTURING THE SAME

Lars Oscar Bergström, Bofors, and Janne Olof Persson, Karlskoga, Sweden, assignors to Aktiebolaget Bofors, Bofors, Sweden, a corporation of Sweden

Filed Jan. 3, 1957, Ser. No. 632,333

Claims priority, application Sweden Jan. 11, 1956

4 Claims. (Cl. 102—8)

The present invention relates to explosive ammunition and a method of manufacturing the same.

The term "ammunition" as herein used, is intended to encompass stationary ammunition, for instance land mines such as anti-tank mines and also ballistic missiles such as shells, the war heads of rockets, etc.

Land mines such as anti-tank mines the explosive material of which is placed in a metal casing, can be rather easily detected, however carefully concealed, for instance, by a burying below the surface, by well known electrically operated mine detectors responsive to the metal of the casing. To avoid such detection, the metal casing of the mines has been replaced by a casing made of a suitable plastic, for instance, a plastic known as Bakelite or specially treated cardboard. Mines with such a casing cannot be detected by mine detectors as now known, but it was found that the keen sense of smell of trained dogs can easily locate the mines by the odor of the plastic casings.

An attempt has been made to eliminate entirely the use of a special casing by casting explosive material in the appropriate shape. Such mines cannot be easily detected either by mine detectors or dogs, but it was found that the mechanical strength of the cast explosive material is inherently too low for the purpose. Attempts have been made to reinforce the mine body by mixing fibre material of suitable length in the liquefied explosive material. However, these attempts have failed as the fibre material tends to bunch so that the hardened mine body lacks reasonable uniform strength.

Accordingly, one of the objects of the present invention is to provide a novel and improved ammunition of the land mine type which when concealed cannot be detected by detectors responsive to metal or by the odor of its casing yet possesses a strength fully adequate for the purpose.

Another object of the invention is to provide a novel and improved piece of ammunition which utilizes as a casing a special re-enforced layer which is formed out of the explosive material and hence participates in the explosive effect thereby amplifying same.

Still another object of the invention is to provide a novel and improved casing made of explosive material and of considerable strength which casing is suitable for use as a shell casing, a casing for the war head of a rocket, a casing for a land mine etc., and which if used as the casing for a land mine affords the specific advantage of defying detection by its odor.

A further object of the invention, allied with the preceding ones, is to provide a novel and improved method of manufacturing ammunition of the general kind above referred to.

A still further object of the invention is to provide a novel and improved method of manufacturing ammunition in which liquefied but hardening explosive material is layered, the outermost layer being reinforced and constituting the casing of the ammunition.

Yet a further object of the invention is to provide a

2

novel and improved method of producing ammunition of the general kind above referred to, by casting one or several layers of the same or different explosive material within a hollow mold from which the finished ammunition can be conveniently removed.

Other further objects, features and advantages of the invention will be pointed out hereinafter and set forth in the appended claims forming part of the application.

In the accompanying drawing several preferred embodiments of the invention are shown by way of illustration and not by way of limitation.

In the drawing:

Fig. 1 is a sectional view of a mold for manufacturing a land mine according to the invention, the method of manufacture being shown in an initial stage.

Fig. 2 is a sectional view similar to Fig. 1, but showing a more advanced stage of the manufacture.

Fig. 3 is a sectional perspective view of the mold and the explosive material therein showing a still more advanced stage of the manufacture.

Fig. 4 is a perspective sectional view of a mold designed for producing a casing according to the invention for a shell, and

Fig. 5 is a sectional view of a completed shell casing according to the invention while being removed from the mold.

Referring first to Figs. 1, 2 and 3 in detail, the exemplification of the invention according to these figures, shows two halves 1 and 2 of a mold for manufacturing the casing for a land mine. One or several protrusions or inserts may be provided within the mold to serve as mounting lugs for parts which have to be fitted in the body of the casing or the finished mine. The half 1 of the mold shown as the upper part thereof is formed with an aperture 3 in which is fitted an internally threaded cup or sleeve 4 intended to protrude into the body of the casing. Sleeve or cup 4 may be used to receive the firing mechanism of the mine or a part of the mechanism.

The mold cavity defines the usual, generally oval or lenticular shape and has at diametrically opposite points of its peripheral rim two apertures in which plugs 5 and 6 are threaded. The apertures for the plugs, when the same are removed, serve as air vent and filling openings respectively. Aperture 3 may also be used for this purpose.

In the first stage of manufacture, the cavity of the mold is lined with a fibrous layer 7 in a manner such that the material of the layer forms in effect a more or less coherent fabric. The layer material should be such that mine detectors do not respond thereto. Glass wool has been found suitable for the purpose. After the formation of layer 7, the cavity is filled with a liquefied, but hardening explosive material 8. This explosive is poured into the mold through one or two of the openings therein, one of the openings being reserved as an air vent.

In the event opening 3 is utilized as a filling opening, sleeve or cup 4 is subsequently inserted. The filled-in explosive will begin to harden from its outside surface toward its interior and after an appropriate length of time, depending upon the characteristics of the explosive employed, a sufficient quantity of the explosive will have hardened to form a wall of appropriate thickness. Plugs 5 and 6 which have been reinserted upon completion of the filling operation are now removed and the part of the explosive still liquefied is poured out as shown in Fig. 2, leaving in the mold a casing of the desired wall thickness and reinforced by the fiber material embedded therein. The mold is thereupon refilled either with the same explosive or with another suitable liquid explosive. After the second filling has hardened enough to form a second layer usually adhesive to the first layer, the remaining still liquefied explosives is poured out. In

this manner any desired number of layers may be cast. However, in many cases, it has been found that a casing, the wall of which is formed of a single layer, is sufficient for the purpose.

The remaining final cavity within the casing is thereupon filled through one of the openings with a desired explosive material. It has been found that suitable explosives for casting the casing proper are explosives such as T.N.T., tritolal, torpex and cyclotol.

As is apparent from the previous description, the liquefied explosive material forming the first layer will penetrate into the interstices of the fiber material forming layer 7 thereby binding with the fibres and becoming reinforced by the same. Fig. 3 shows the casing ready to be filled with the additional explosive.

Referring now to Figs. 4 and 5, the mold according to these figures is designed, as previously mentioned, to produce the casing of a shell of conventional configuration. The mold comprises two halves 1' and 2' which may be joined to each other by a conventional screw joint. The upper half 1' of the mold for forming the nose end of the shell casing has an axial bore 3' in which a sleeve 4' can be fitted to form a housing for the percussion fuse or other firing mechanism of the shell. The lower half 2' of the mold also has an axial bore 5' for receiving a sleeve that is intended to extend in the body of the finished shell casing. Sleeve 6' serves to house another part of the firing mechanism.

In the first stage of manufacture, the inner wall of the mold is lined with a reinforcement layer 7' in the form of a fabric layer. Layer 7' may be made of glass wool or of metal especially metal threads since the problem of detection is not present with shell casings.

In the next stage of production a hollow feed tube 9 is inserted in the mold cavity through bore 3'. This tube can be rotated by suitable drive means and also be moved up and down within the mold cavity. It should be visualized as being connected to a supply of suitable liquefied explosive material. To cast the casing of the shell in accordance with the invention, tube 9 is lowered within the mold to a point at which its mouth is close to the bottom of the mold and then rotated while being slowly raised. As a result, the liquid explosive material which leaves the tube through the bottom and/or lateral openings thereof is thrown by the centrifugal force against the wall of the mold cavity and more specifically upon the layer 7' lining the same. As is evident, the explosive material when hardening will form a coating along the inner wall of the mold and penetrate into the interstices of the material forming liner 7'. The thickness of the coating can be conveniently controlled by the speed at which tube 9 is raised within the mold. After the coating is hardened, any number of additional coatings may be formed in the same manner, either of the same explosive material or a different one depending upon the specific requirements. The remaining final cavity is then filled with a suitable explosive material in the same manner as the conventional casing of a shell.

As is obvious from the previous description, casings for other kinds of ammunition having a rotation symmetric configuration as shown in Figs. 4 and 5 can be produced in the same manner, that is, by distributing the explosive material upon a reinforcement layer lining the mold cavity by spinning the feed tube 9. In this connection, it may be mentioned that the same effect as is obtained in Figs. 4 and 5 by rotating tube 9, can also be procured by rotating the mold proper, or rotating both the feed

tube and the mold. Similarly, the mold of Figs. 1 to 3 may be partly filled only and rotated about an appropriate axis to distribute the liquefied explosive material over fiber lining 7.

Tests have shown that casings according to the invention, that is, casings having a wall made of explosive material including uniformly distributed reinforcement material, possess a very considerable strength. It has been found that casings for land mines are capable of withstanding a load of about 2,000 kg. when the cavity of the casing is filled with explosive material.

While the invention has been described in detail with respect to certain now preferred examples and embodiments of the invention it will be understood by those skilled in the art after understanding the invention, that various changes and modifications may be made without departing from the spirit and scope of the invention, and it is intended, therefore, to cover all such changes and modifications in the appended claims.

What is claimed as new and desired to be secured by Letters Patent, is:

1. A self contained explosive land mine comprising, in combination, an external reinforcing layer, a plurality of discrete internal cast layers of hardened explosive material enveloped by said external reinforcing layer, said external reinforcing layer including a fabric skeleton of inter-meshing fibrous material embedded in the outermost one of said internal cast layers, the explosive material of said outermost internal cast layer penetrating into the interstices of said fibrous material bonding said external reinforcing layer to said outermost internal cast layer.

2. A casing according to claim 1, wherein said fabric is made of glass wool.

3. A casing according to claim 1, wherein said fabric is made of metal threads.

4. A method of producing ammunition of the kind described, comprising the steps of lining a mold cavity defining the outer configuration of a casing with a layer of fibrous intermeshing material, inserting in the mold cavity a feeder tube for feeding hardening liquefied explosive material into the lined cavity, displacing the discharge end of said tube axially within the mold cavity between the top and the bottom thereof and simultaneously rotating the mold and the tube relative to the mold about its longitudinal axis, whereby the explosive material is applied by centrifugal force to said fibrous liner penetrating into the interstices thereof, allowing time for hardening of the explosive material filling said interstices, removing still liquid explosive material whereby the remaining hardened explosive material constitutes a casing reinforced by the fibrous material embedded therein, and filling the interior of said casing with explosive material.
